United States Patent

Des. 240,176
Patented June 8, 1976

240,176

SEAT

Alan H. Friedman, Millburn, N.J., assignor to
Futorian Corporation, Amsterdam, N.Y.

Filed May 28, 1974, Ser. No. 473,612

Term of patent 14 years

Int. Cl. D6—01

U.S. Cl. D6—63

FIG. 1.

FIG. 3.

FIG. 2.

FIG.4.

FIG.5.

FIG.6.

FIG. 7.

FIG. 1 is a side perspective view of a seat illustrating my design in the form of a sofa;

FIG. 2 is a front perspective view of the seat of FIG. 1 shown in the form of a loveseat;

FIG. 3 is a side perspective view of the seat of FIG. 1 shown in the form of an armchair;

FIG. 4 is a front perspective view of the seat of FIG. 1;

FIG. 5 is a side perspective view of the seat of FIG. 1 shown in the form of a loveseat but wherein the side panels are formed of nonrigid material and the armrests are provided with upholstery buttons;

FIG. 6 is a modified form of the seat of FIG. 1 shown in the form of an armchair but wherein the side panels are formed of nonrigid material and the armrests are provided with upholstery buttons; and

FIG. 7 is a perspective view of the seat of FIG. 6 on an enlarged scale.

The rear surfaces of the several embodiments are conventional in configuration while the side of each embodiment not shown is a mirror image of the side shown.

I claim:

The ornamental design for a seat, as shown and described.
